W. C. JAMES.
SANITARY KITCHEN, LAVATORY, AND LAUNDRY APPLIANCE.
APPLICATION FILED DEC. 26, 1905.

Patented July 7, 1914.

UNITED STATES PATENT OFFICE.

WILLARD C. JAMES, OF LOS ANGELES, CALIFORNIA.

SANITARY KITCHEN, LAVATORY, AND LAUNDRY APPLIANCE.

1,102,411.

Specification of Letters Patent.

Patented July 7, 1914.

Application filed December 26, 1905. Serial No. 293,212.

To all whom it may concern:

Be it known that I, WILLARD C. JAMES, a citizen of the United States, residing at Los Angeles, in the county of Los Angeles and 5 State of California, have invented a new and useful Sanitary Kitchen, Lavatory, and Laundry Appliance, of which the following is a specification.

An object of this invention is to provide 10 superior convenience for the house-wife or servant in an apartment designed to be used for kitchen, laundry and lavatory purposes.

The accompanying drawings illustrate the invention.

15 Figure 1 is an elevation of my newly-invented apparatus, the same being in mid-section through the main portion of the view; the drain-board is shown raised in solid lines, and closed in dotted lines. Fig. 20 2 is a fragmental detail of the upper portion of the connection between the tub and the wash-bowl. Fig. 3 is a fragmental detail of the outlet of the tub with the sink connection shown just withdrawn. Fig. 4 is a 25 fragmental detail illustrating the plugged outlet from the wash-bowl. Fig. 5 is an elevation from the right of Fig. 1 showing the wash-bowl and drain-board intact, the drain-board being lowered. Dotted lines indicate shifted position of the drain-board.

30 1 is a tub; 2, the outlet therefrom; 3, the overflow from the tub communicating with the outlet 2 thereof.

4 is a removable sink fitting the mouth of 35 the tub and provided with an outlet 5.

6 is a removable stand pipe removably seated in the outlet 2 and having an open mouth just below the outlet 5 of the sink so that by simply seating the sink in place the 40 connection between the sink and the outlet is made and when the sink is withdrawn the stand pipe 6 will form an automatic overflow for the tub through the outlet 2 of the tub.

45 7 is a wash-bowl having in its bottom an outlet 8, and also having an overflow 9 communicating with the outlet, said outlet communicating through pipe 8' with the overflow 3 of the tub.

50 10 is the trap of the outlet 2 of the tub.

11 is a faucet provided with a pivoted bib 12 adapted to discharge into the wash-bowl, sink, and tub alternately.

55 13 is a drain-board shiftably hinged to the wash-basin at 14, and adapted to shift

to escape the faucet 11, and to close and open the wash-bowl 7.

The connection 6 between the outlet of the sink and the outlet of the wash-bowl comprises a pipe 15 having a flaring mouth 16 60 and terminating in a laterally perforated plug 17, the lateral perforations 18 thereof being designed to receive the water from the overflow 3; the connection 6 being tubular throughout from top to bottom so that the 65 water from the sink flows freely through the connection when the same is in place as shown in Fig. 1, and at the same time water from the wash-basin 7 and from the overflow 3 of the tub will flow freely from the 70 plug into the trap 10 which forms the outlet from the tub.

19 is a plug for the wash-basin, the same being provided with lateral openings 20 to leave the overflow 9 open while the plug is 75 inserted.

It is apparent that the parts are all readily accessible by removing the connection 6 and the plug 19.

The drain-board 13 may be of stamped 80 steel or any other suitable material and hinged below the ledge of the wash-bowl 7 by lugs 21 and pin or rod 22, which may be alternatively connected, one to the drain board and the other to the ears 23, or other 85 suitable support. In the drawings the lugs 21 project from a standard 24 and are provided with a hook and stop 25 to hook over the rod 22, which is supported by the ears 23, and to engage the ledge 26 of the wash-bowl to stop the drain-board 13 and hold it 90 aslant after it has passed an upright position, as shown in Fig. 1.

27 is the usual bracket for supporting one 95 end of the wash-bowl.

The manner of using the appliance will be understood from the foregoing description.

What I claim is:

1. A tub provided with an outlet and an overflow, a sink provided with an outlet detachably mounted in the tub, a discharge pipe removably seated in the outlet and arranged to receive the discharge from the sink outlet; a wash-bowl provided with an outlet and an overflow communicating with each other and with the trap of the tub through the overflow; a faucet provided with a swinging bib arranged to discharge into the wash-bowl, sink and tub alternately, and a detachable drain-board hinged 105 110

- to fold over the wash-bowl and slidingly mounted to shift to escape the faucet in the act of raising and lowering.
2. A tub provided with an outlet at its lower end, a sink removably mounted in the tub and provided with an outlet, a wash bowl having an outlet, a connection between the bowl and sink outlets, and a perforated plug at the junction of said connections and positioned to drain both the sink and the bowl at the same time without draining the tub.
3. A wash-bowl, a sink mounted beside the wash-bowl, a faucet midway between the bowl and the sink and having a pivoted bib by means of which it may be swung back and forth from the bowl to the sink as desired, a drain-board to cover the wash-bowl, one end of it projecting over the sink and the other end pivotally and slidingly mounted upon a lateral pivotal rod and adapted to a forward movement to clear the faucet and an upward movement to clear the bowl.
4. A sanitary kitchen lavatory and laundry appliance, comprising a tub, a wash-bowl and a drain-board and a detached hinge connecting the wash-bowl and the drain-board, and provided with a standard for raising the upper end of the drain-board and with a hook and stop to engage the wash-bowl, substantially as and for the purpose set forth.
5. The combination with a stationary tub having an outlet at its bottom, of a sink removably mounted in the tub, and a removable connection adapted to be inserted in the outlet of the tub and to receive and carry the drainage from the sink, a wash-bowl mounted beside the tub, and a perforated 40 drainage connection between the wash-bowl and the outlet of the tub so that the wash-bowl and the sink may be drained at the same time.
6. The combination with a stationary tub 45 having an outlet at its bottom and an overflow leading to the outlet, of a sink removably mounted in the tub, a removable connection having a plug-shaped lower end adapted to fit closely in the outlet of the tub 50 so as to hold water in the tub and so as to drain the sink, a wash-bowl mounted beside the tub and having an outlet and an overflow leading to the outlet, and a drain from the outlet of the wash-bowl into the overflow 55 of the tub so that the sink and wash-bowl may be drained simultaneously without draining the tub.
7. A tub provided with an outlet and an overflow, a sink provided with an outlet detachably mounted in the tub, a discharge pipe removably seated in the outlet and arranged to receive the discharge from the sink outlet; a wash-bowl provided with an outlet and an overflow communicating with each other and with the trap of the tub through the overflow, and a faucet provided with a swinging bib arranged to discharge into the wash-bowl, sink and tub alternatively.
- In testimony whereof, I have hereunto set my hand at Los Angeles, California this 16th day of December 1905.
- WILLARD C. JAMES.
- In presence of—
JAMES R. TOWNSEND,
JULIA TOWNSEND.
